UNITED STATES PATENT OFFICE.

WALTHER HELLMUTH GREIFENHAGEN, OF MUNICH, GERMANY.

DROP-FLASK.

No. 841,684.

Specification of Letters Patent.

Patented Jan. 22, 1907.

Application filed February 16, 1906. Serial No. 301,474.

To all whom it may concern:

Be it known that I, WALTHER HELLMUTH GREIFENHAGEN, a subject of the King of Bavaria, residing at Munich, Germany, have invented certain new and useful Improvements in Drop-Flasks, of which the following is a specification.

This invention relates to improvements in drop-flasks.

Various devices are used for the purpose of introducing small quantities of liquid into cavities more particularly with the object of treating diseases of the human body; but the cost of the most efficient devices hitherto known for this purpose is so considerable as to practically necessitate the repeated use thereof, so that danger of blood-poisoning or injection is involved. For this purpose it is desirable to provide for the purpose indicated a cheap device which can without involving considerable expense be destroyed after being once used. Several devices which have been designed with this object in view are for various reasons inefficient in their action. In some cases the means for fastening the receptacle are not sufficiently secure to prevent premature evaporation of the antiseptic or medicinal substance contained in the said receptacle. In other cases, more particularly in those in which collapsible tubes are used, the receptacle is not adapted to contain a liquid and can only be used for viscous substances. The known cups or flasks with narrow orifices normally closed by means of a soft substance—such as wax, gelatin, or the like—have the disadvantage that portions of the said substance are liable to become mixed with the liquid in the receptacle or that even the entire plug or stopper may be dissolved or decomposed by the said liquid.

The object of the present invention is to provide a device for introducing drops of antiseptic or medicinal liquid into small cavities of the human body without involving any of the disadvantages hereinbefore indicated.

The invention is illustrated in the annexed drawings, in which—

Figure 1 is an elevation of the device, and Fig. 2 a view illustrating the manner in which the latter is used.

The device comprises a glass tube *a*, of suitable length and diameter, hermetically closed at both ends by means of plugs *c* and *d*, of cork or other suitable material. The lower orifice of the said tube is considerably smaller than the upper orifice, so that it can be conveniently introduced into small cavities—for instance, into the penis. The essential novel feature of the device consists, however, in the constriction *b* between the orifices of the tube *a*, which produces a narrow duct or passage at the central part of the said tube, the diameter of the duct or passage being such that only a portion of the contents of the tube can flow from the latter through the smaller orifice, even when both orifices are open. This arrangement not only allows of easily obtaining the discharge of the liquid in the form of drops, but also facilitates the closing of the discharge-orifice.

For use the plug or stopper *c* is first removed from the discharge-orifice and the empty portion of the tube between the said orifice and the constriction *b* is thereupon introduced into the part to be treated. Thereupon the upper plug or stopper *d* is removed, as shown in Fig. 2, and the liquid is thus enabled to flow in the form of drops into the said part. The cost of the small tube and its contents is so small that practically no material loss is involved by destroying it immediately after use.

What I claim as my invention, and desire to secure by Letters Patent of the United States, is—

A medicinal drop-flask having a large orifice at one end and a small orifice at the other end and a constricted passage-way intermediate of its ends adapted to permit passage of liquid drop by drop only, the body of the flask toward the smaller end being tapered to the small orifice at the end thereof for the purpose described.

In witness whereof I have signed this specification in the presence of two witnesses.

WALTHER HELLMUTH GREIFENHAGEN.
